HENRIETTE B. WOEHRLE, OF NEWARK, NEW JERSEY, ASSIGNOR TO THE SINGER
MANUFACTURING COMPANY, A CORPORATION OF NEW JERSEY.

SEWING-MACHINE RUFFLER.

1,118,254.

Specification of Letters Patent.

Patented Nov. 24, 1914.

Application filed March 23, 1912. Serial No. 685,703.

To all whom it may concern:

Be it known that I, HENRIETTE B. WOEHRLE, a citizen of the United States, residing at Newark, in the county of Essex and State of New Jersey, have invented certain new and useful Improvements in Sewing-Machine Rufflers, of which the following is a specification, reference being had therein to the accompanying drawings.

10 This invention relates to an improvement in ruffling devices for sewing machines, and it has for its object to provide means whereby shirring in the body of the fabric may be reinforced to prevent its disarrangement 15 in subsequent use, and also to provide means for insuring the parallelism of a series of spaced shirring seams.

The invention is preferably embodied in a ruffling attachment constructed with a 20 frame comprising a foot portion and a shank adapted for attachment to the presser-bar of a sewing machine, and having a reciprocating ruffling blade connected with a forked operating lever embracing a stud carried by 25 the sewing machine needle-bar. The shirring plate is sustained by a frame secured upon the sewing machine bed-plate, and is provided with a shirring blade formed with apertures extending through it in line with 30 the notch in its forward edge embracing the needle-path, for the reception of a reinforcing tape or cord which is stitched upon the lower face of the fabric as the crimping and stitching progresses. The presser- 35 foot shank has preferably secured thereto a transverse spring-socket to receive the sustaining rod of a seam gage adapted to follow each preceding shirring seam to insure uniformity of spacing therefrom of the succeeding seam.

The invention will be understood by reference to the accompanying drawing, in which—

Figure 1 is a perspective view of the forward portion of a sewing machine provided with a ruffling device embodying the present invention; and Fig. 2 a similar view of the shirring plate and its holding frame, and representing a piece of narrow tape introduced within the guiding apertures of its blade. Fig. 3 is a face view of the shirring blade detached, and Fig. 4 is a view of the under side of a section of material provided with a reinforced shirring seam pro-

duced by the use of the present improvement.

The sewing machine bed-plate 1 is shown provided with the usual throat-plate 2 formed with the apertures 3 for the feed-dog 4, and has also the usual slide-plate 5 abutting against the adjacent edge of the throat-plate. In the head 6 of the bracket-arm is journaled the usual reciprocating needle-bar 7 provided with the needle-clamp 8 having secured therein the needle 9 by means of a laterally projecting clamp-screw 10, only a portion of which latter is exposed in Fig. 1. In the head 6 is also fitted the presser-bar 11 with reduced lower end 12 to receive the usual presser-foot.

As represented in Fig. 1, the ruffling attachment comprises a frame constructed with a presser-foot having the yielding pressure member 13 with a shank 14 adapted to be secured to the presser-bar by means of the clamp-screw 15. Upon the arm 16 of the ruffer-frame is sustained the fulcrum-pin 17 upon which is mounted the operating lever 18 having the fork 19 embracing the needle-clamp screw 10. The lever 18 has a lip or shoulder 20 adapted for alternate engagement with the lateral seat 21 and the point of the screw 22 carried by the lever 23 also journaled upon the fulcrum-pin 17 and connected at its lower end by means of the pivotal pin 24 with the rearward end of the slide-bar 25 suitably guided and having secured thereto by means of the rivets 26 the reciprocating ruffling blade 27. The ruffling-blade is formed with a center notch 28 or aperture 27, providing at each side thereof a fabric engaging member. The notched and apertured guide-plate 28, disposed above the ruffling blade, is sustained in position by means of the arm 29 secured to the presser-foot.

The substantially crescent-shaped frame-plate 30 is provided at its extremities with depending lips 31 with inturned spring-arms 32 to afford hooks which embrace the forward edge of the throat-plate 2 in interlocking relation with which they are maintained by the adjacent edge of the slide-plate 5, as represented in Fig. 1. The frame-plate 30 is formed with a lateral ear 33 to which is secured by means of rivets 34 one end of a shirring plate 35 having attached thereto by means of the rivets 35,

passing through holes 36 therein, the shirring blade 37 having in its opposite operative end the needle-clearance notch 38 and in alignment with the latter the two 5 guiding apertures 39, passing entirely through the same and disposed near its operative or fabric engaging end so as to deliver the reinforce-strip close to and in register with the needle-path. The fabric-engaging members of the ruffling blade operate at opposite sides of the guiding apertures 39. The shirring plate 34 has the usual series of fabric-guiding slots 40 and 41 extending in opposite directions crosswise of the shirring blade 37.

Secured to the presser-foot shank by means of the rivet 42 is the plate 43 provided at one end with the arched spring socket-member 44 adapted to yieldingly sustain between itself and the presser-foot shank the rod 45 forming the stem of the gage-plate 46 adapted to be set with one extremity near the top of the fabric-supporting slide-plate 45 for guiding the fabric in a shirring operation. The rod 45, being yieldingly clamped in position, is adapted to be readily turned and shifted endwise for adjustment of the gage-plate 46 as desired.

Preparatory to a shirring operation, the strip *s* of reinforcing material is introduced beneath the plate 34 and threaded successively upwardly and downwardly through the guide-apertures 39 of the shirring blade 37 and thence through the needle-clearance notch 38. The fabric *f* is then introduced between the ruffling and shirring blades and the shirring and stitching operation then performed, whereby the strip *s* is secured by means of the line of stitches *t* upon the under face of the shirred fabric, as represented in Fig. 4. When a succession of

spaced and parallel shirring seams is desired, the gage-plate 46 is set in required position, and the fabric is fed in a manner well known to cause the gage to follow the previously formed line of stitching.

Having thus set forth the nature of the invention, what I claim herein is:—

1. In a ruffling attachment, the combination with the frame, a ruffling blade, and actuating means therefor, of a shirring-plate cooperating with the ruffling blade, a shirring blade carried by said shirring-plate and formed with a needle-aperture and with two parallel slots intermediate said needle aperture and the shirring plate, the said slots having walls adapted to maintain the center line of a reinforcing tape in fixed relation to said needle-aperture, and fabric-engaging members carried by the ruffling blade to engage the fabric at opposite sides of said slots.

2. In a ruffling attachment, the combination with the frame, a ruffling blade and actuating means therefor, of a shirring-plate cooperating with the ruffling blade, a shirring blade carried by said shirring-plate and formed with a tape-guide slot adjacent its operative edge and with a parallel slot adjacent the shirring plate, the walls of said slots comprising means for preventing lateral movement of the tape, and fabric-engaging members carried by the ruffling blade to engage the fabric at opposite sides of said tape-guide slots.

In testimony whereof, I have signed my name to this specification, in the presence of two subscribing witnesses.

HENRIETTE B. WOEHRLE.
